UNITED STATES PATENT OFFICE.

SAMUEL L. ALLEN, OF CINNAMINSON, NEW JERSEY.

DESIGN FOR A CULTIVATOR-BLADE.

SPECIFICATION forming part of Design No. 19,712, dated March 25, 1890.

Application filed February 7, 1890. Serial No. 339,609. Term of patent 14 years.

To all whom it may concern:

Be it known that I, SAMUEL L. ALLEN, a citizen of the United States, residing at Cinnaminson, in the county of Burlington and State 5 of New Jersey, have invented and produced a new and original Design for a Cultivator-Blade, of which the following is a full specification, reference being had to the accompanying drawing, forming a part thereof.

The drawing represents a plan view of a cultivator-blade embodying my design.

The leading feature of my design consists in a cultivator-blade having a convexly curved advancing edge and having two unequal outwardly and rearwardly extending wings forming an obtuse angle with each other, the two wings being separated by a curved ridge between them.

A is the blade, having two outwardly and 20 rearwardly extending wings A'A², which form

an obtuse angle with each other. These two wings A'A² are similarly shaped and of the same width; but one of them is much longer than the other, so that the blade is unsymmetrical. The tops of the two wings are 25 straight and are connected by the smooth curve d, while the bottoms are convexly curved, as at b c, the ridge between the two wings terminating in a convex advancing edge a, the curve of which connects smoothly 30 with the concaved edges b and c.

I claim—

The design for a cultivator-blade herein shown and described.

In witness whereof I have hereunto set my 35 hand.

SAMUEL L. ALLEN.
